UNITED STATES PATENT OFFICE

LEVI S. HOWLAND, OF OAKLAND, CALIFORNIA

DIRIGIBLE CONSTRUCTION

Application filed September 27, 1927. Serial No. 222,239.

My present invention relates to dirigible construction.

The objects of this invention are; first, to provide a dirigible which may be taken off directly from the ground or landed on the ground, if desired; second, to provide a dirigible which can be readily handled in the air, which can be made to ascend and descend rapidly, and which can be steered directionally easily; third, to provide a dirigible which does not require the sensitive balance now required in dirigibles, and one in which the lifting power is not dependent directly upon the inflated balloon; fourth, to provide a dirigible from which the power units or power vanes may be easily and quickly disconnected and others substituted; fifth, to provide a dirigible of this class having disconnectible power units or power vanes in the form of airplanes which may be readily handled by taxiing the same on the ground; sixth, to provide a dirigible of this class in which the cabins and power units are complete units separable from the bag of the dirigible; seventh, to provide a dirigible having detachable cabins provided at the opposite sides with power units disconnectible from the bag of the dirigible with the cabins; eighth, to provide a dirigible of this class having disconnectible cabins provided with power units, which power units may also be disconnected from the cabins; ninth, to provide a dirigible of this class having power units pivotally suspended from the bag of the dirigible so that the same may be tilted, as desired, for easily raising, lowering, or tilting the dirigible; tenth, to provide a dirigible of this class having controls at the tail end for general handling of the dirigible, and also other controls on the individual power vanes for special and rapid control of the dirigible; eleventh, to provide as a whole a novelly constructed dirigible; and, twelfth, to provide a dirigible of this class which is relatively simple of construction proportionate to its functions, efficient, safe, and which will not readily deteriorate or get out of order.

With these and other objects in view, as will appear hereinafter, my invention con-

sists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a side view of my dirigible in its preferred form of construction, portions of the balloon being broken away for convenience of illustration, the cabins and power vanes being slightly exaggerated for convenience of illustration; Fig. 2 is a fragmentary front elevational view thereof, the intermediate and aft power vanes being indicated diagrammatically by dotted lines; and, Fig. 3 is a perspective view showing a complete unit comprising a cabin and a power vane on each side, as the same appears disconnected from the balloon of the dirigible.

Like characters of reference refer to similar parts and portions throughout the several views of the drawings.

The balloon portion or hull 1 and the horizontal stabilizers 2, elevators 3, vertical stabilizers 4 and the rudders 5 at the tail or aft end of the hull, are substantially or may be of the same construction as those of conventional rigid type dirigibles now in use. The parts referred to, however, comprise a complete and separate unit from the several pilot, passenger, or other cabins, the engine gondolas, and the means for supporting the cabins and gondolas on the hull.

In my dirigible, illustrated in the drawings, I have shown three separate cabins, namely, the forward cabin 6 which may be used as a pilot's cabin or navigating room, a radio room, and officers' quarters, the midship cabin 7 which may serve as the passenger cabin, passenger sleeping quarters and mess hall for passengers and crew, and the aft cabin 8 which may serve as crew's quarters, store space, or other purposes. Each cabin, whether 1, 2, 3, or more, is provided at its opposite lateral sides with a power vane or power unit which is connected to the cabin and may be separated as a unit therewith from the hull of the dirigible, as shown in

Fig. 3. The cabins may be variously attached to the underside of the hull, as shown, the forward and aft cabins being attached thereto by struts and the midship being directly attached to the underside thereof by means such as bolts. The cabins 6 and 7 are preferably provided with rigid struts which extend outwardly from the upper portion thereof and are connected by bolts at their ends to sockets in the hull of the dirigible. The forward struts 9 extend preferably laterally and forwardly, while the rear struts 10 extend laterally and backwardly. The intermediate struts 11 and 12, there being preferably two at either side, may extend laterally only, as shown. The power vanes, or power units, designated 14, are pivotally supported intermediate their ends by bifurcated frames or yokes 13. Each yoke is pivotally and yieldably connected to the cabin and the hull by a plurality of struts. Referring particularly to Fig. 3, the inner side of the yoke is pivotally connected near its upper end and at its forward and rear edge portions to the outer ends of struts 15 and 16, respectively, which are pivotally connected at their inner ends to the outer ends of the struts 11 and 12 near the ends connected to the hull. The same side of the yoke below the pivotal connection with the struts 15, is pivotally connected to the outer end of a tension and shock absorbing strut 17 which is provided at the end adjacent the cabin with a tension shock absorber 18 which is pivotally connected to the cabin. The outer side of the yoke is pivotally connected to the lower ends of struts 19 and 20, the former extending forwardly and pivotally connected directly to a fitting on the hull, while the latter extends backwardly and is pivotally connected at its rear and upper end to the end of a plunger 21a of the compression shock absorber 21 preferably mounted within and supported by the frame of the hull. Thus, when the power vane is subjected to a shock, as when landing, the same is held outwardly from the cabin by the struts 15 and 16 but permitted to be shifted upwardly and backwardly, the strut 17 taking a portion of the shock by the tension shock absorber and the strut 20 taking a portion by the compression shock absorber 21. The power unit, or power vane, consists of a body 14a in the form of an airplane fuselage having a motor at its forward end and a propeller operated by the motor, an undercarriage 14b at the underside of its forward end portion, supporting planes 14c extending to either side from near the forward end to the rear end of the body 14a and preferably diverging toward the rear end of the body, a vertical stabilizer extending from the body at the rear end thereof, elevators 14e pivotally connected to the trailing edge of the plane surfaces 14c, and a rudder 14f pivotally connected to the trailing edge of the vertical

stabilizer 14d. Thus, it will be seen that the power unit, or power vane, is constructed similarly to an airplane with limited supporting surfaces. The undercarriage 14b is preferably provided with only one large wheel, or a pair of wheels positioned close together. The supporting surfaces or wings 14c are preferably positioned slightly below the center of gravity. The pivotal connection of the body of the power vane to the yoke, or the lower furcated ends thereof, is on a horizontal axis extending through the center of gravity of the power vane so that the power vane is substantially balanced at all times. The cockpit of the power vane is preferably positioned forwardly of the yoke so that the field of vision of the operator of the power vane will not be obstructed. To limit the tilting movement of the power vane relative to the supporting yoke, I have provided stop members 14g on the exterior of the body 14a forwardly and backwardly of the yoke which limit the tilting movement of the power vane. The operator of each power vane controls only his engine and the elevators and rudder, but is directed in such control by suitable signalling mechanism operated from the pilot's cabin by the pilot, as in ship and dirigible construction now in use. If the operator is directed to incline his particular power vane either upwardly or downwardly, (the rear power vane being shown directed downwardly), he operates his controls to the degree designated, the controls for the motor, elevators and rudder being held in the directed position by suitable mechanism, such as frictionally retained levers. By the control of the separate power vanes from the pilot's cabin, the dirigible may be made to rise rapidly, descend rapidly, or to change direction rapidly. The general directional and elevational control is effected by the pilot in the usual manner by manipulating the elevators 3 and the rudders 5.

When landing, the dirigible may be landed on the ground as is common with the landing of airplanes, or the same may be anchored at a terminal in any other manner desired.

When landing the separate power vanes independently of the dirigible, the same may be taxied on the ground as an ordinary airplane. In order to stabilize the same, I have provided a pair of tail skids 22 near the trailing and lateral edges of the wing surfaces, as shown in Figs. 1 and 2.

Intercommunication between the several power vanes and the cabins may be effected by ladders 23 supported by the struts 19, which ladders are directed to openings in the hull from which openings passages or gangways may lead to the keel runway, designated 24 in Fig. 2.

Though I have shown and described a particular construction, combination and arrangement of parts and portions, I do not

wish to be limited to this construction, combination and arrangement, but desire to include in the scope of my invention the construction, combination and arrangement substantially as set forth in the appended claims.

5 Having thus described my invention, what I claim as new and desire to secure by Letters Patent is:

1. In a dirigible, a hull, frames yieldably and resiliently mounted on and extending from the hull, and a plurality of power units pivotally mounted on the extended ends of the frames, said power units having undercarriages to facilitate the landing and taking off of the dirigible.

10 2. In a dirigible, a hull having a depending framework, and a power unit pivotally mounted intermediate its ends on said depending framework, said power unit comprising a fuselage by which the power unit

25 is supported, a motor and propeller at the forward end of the fuselage, wing surfaces at the sides and extending the full length of the fuselage and control surfaces at the rear end thereof.

30 3. In a dirigible, a hull having a depending framework, and a power unit pivotally mounted intermediate its ends on said depending framework, said power unit comprising a fuselage by which the power unit

35 is supported, a motor and propeller at the forward end of the fuselage, wing surfaces at the sides of the fuselage, control surfaces at the rear end thereof, an under carriage

40 at the forward end of the fuselage and laterally and widely spaced tail skids at the rear end of the power unit and below each wing surface.

45 4. In a dirigible, a hull having a depending framework, and a power unit pivotally mounted intermediate its ends on said depending framework, said power unit comprising a fuselage by which the power unit

50 is supported, a motor and propeller at the forward end of the fuselage, wing surfaces at the sides of the fuselage, control surfaces at the rear end thereof, and a narrow wheel under carriage at the forward end of the lower side of the fuselage and double laterally and widely spaced tail skids at the rear end of the lower side of the power unit and below each wing surface.

55 5. In a dirigible, a cabin readily detachably mounted at the lower side of the hull of the dirigible and provided with a laterally extended framework, and a power unit pivotally mounted on said framework.

60 6. In a dirigible, a cabin readily detachably mounted at the lower side of the hull of the dirigible and provided with laterally extended framework, and a power unit readily detachably mounted on said framework.

65 7. In a dirigible, a hull, a cabin mounted at the lower side of the hull, framework ex-

tending laterally to both sides of the cabin, and power units mounted at the extended ends at both lateral sides of the framework, the whole of the cabin, framework and power units being detachable as a unit from the hull of the dirigible.

8. In a dirigible, a hull, a cabin mounted at the lower side of the hull, framework extending laterally to both sides of the cabin, and power units mounted at the extended ends at both lateral sides of the framework, the whole of the cabin, framework and power units being detachable as a unit from the hull of the dirigible, said power units being readily detachably connected to said framework and provided with independent control surfaces adapted for controlling the dirigible when in the air and for controlling said power units when disconnected from said framework.

85 9. In a dirigible, a hull, and a plurality of landing carriages mounted at the lower side thereof, said undercarriages having laterally and upwardly directed framework, the laterally directed framework being adapted to permit tilting and upward movement of the landing carriages relative to the hull and the upwardly directed framework being adapted to permit upward movement thereof of the carriages and to reduce shock upon the hull when landing the dirigible.

In testimony whereof, I have hereunto set my hand at Los Angeles, California this 15th day of September, 1927.
